VENDING MACHINE

Roy E. Elvers, Los Angeles, Calif.

Application April 2, 1940, Serial No. 327,442

6 Claims. (Cl. 312—70)

My invention relates generally to vending machines and more particularly to the means for supporting the vended articles or commodities within the machine and for effecting discharge of said articles or commodities from the supporting means and also for the handling and storage of the article or product supporting means after each vending operation.

The principal objects of my invention are, to generally improve upon and simplify the construction of the existing forms of vending machines, particularly the article or product supporting and delivery means thereof, further, to provide a vending machine that is devoid of all endless carriers and the chains, cables and gearing associated therewith and further, to provide a vending machine wherein the vended article or product supporting means comprises a plurality of sets of rods or a series of separate racks.

Further objects of my invention are, to provide simple and efficient means for effecting the sequential release of the sets of rods or racks that carry the vended articles or products and further, to provide a machine having a chamber in its lower portion that receives the rods or racks utilized in supporting the vended articles after the latter discharge from the supporting means.

A further object of my invention is, to provide a vending machine that may be utilized for supporting in a chamber or compartment having a glazed front, relatively thin articles or objects to be vended, for instance, newspapers, thin magazines or pamphlets, and the same article supporting means capable of being differently arranged so as to support comparatively thick objects, such as loaves of bread, boxes containing food particles, or the like, or for commodities that are packed in cans.

A further object of my invention is, to provide a vending machine of the character referred to that is especially applicable for use in public markets that specialize in the sale and distribution of groceries and other food products, thus enabling the purchasing public to serve themselves in the purchasing of various desired commodities.

With the foregoing and other objects in view, my invention consists in certain novel features of construction and arrangement of parts that will be hereinafter more fully described and claimed and illustrated in the accompanying drawings in which:

Fig. 1 is a perspective view looking against the front of a structure that is equipped with a vending machine of my improved construction.

Fig. 2 is an enlarged vertical section taken on the line 2—2 of Fig. 1.

Fig. 3 is a horizontal section taken on the line 3—3 of Fig. 2.

Fig. 4 is an enlarged detail horizontal section taken on the line 4—4 of Fig. 2. Fig. 4a is a perspective view of one of the rails that provide supports for the merchandise carrying rods.

Fig. 5 is a detail section taken on the line 5—5 of Fig. 4.

Fig. 6 is an elevational view with parts broken away and looking in the direction indicated by the arrow 6 in Fig. 4.

Fig. 7 is an elevational view similar to Fig. 6 and showing the supporting rod releasing bar in shifted position.

Fig. 8 is a vertical section taken on the line 8—8 of Fig. 7.

Fig. 9 is a vertical section similar to Fig. 2 and showing a modified form of the vending machine.

Fig. 10 is a horizontal section taken on the line 10—10 of Fig. 9.

Fig. 11 is an enlarged detail section taken on the line 11—11 of Fig. 10.

Fig. 12 is a plan view of the parts seen in Fig. 11.

Fig. 13 is a sectional view similar to Fig. 11 and showing the vended article supporting rods in shifted positions.

Fig. 14 is a plan view of the parts seen in Fig. 13.

Fig. 15 is a perspective view of a rack utilized for supporting vended articles in the modified form of the machine illustrated in Figs. 9 and 10.

Fig. 16 is a detail section of a modified construction utilized for holding the goods supporting rods in predetermined spaced relation.

Fig. 17 is a horizontal section taken on the line 17—17 of Fig. 16.

Fig. 18 is a sectional view showing a modified arrangement for supporting the rods that provide supports for the vended articles.

Fig. 19 is a sectional view of a modified construction including an inclined bottom for the machine and which receives the vended articles as they discharge from the supporting means.

Referring by numerals to the accompanying drawings and particularly to Figs. 1 to 8 inclusive, which illustrate a preferred embodiment of my invention, 10—10 designate the side walls of a housing, 11 a top panel, 12 a bottom panel, and 13 a rear wall. The upper portion of the rear wall 13 is provided with an opening that is normally closed by a door 14 in order to give

access to the chamber within the housing or cabinet.

It is to be understood that the vending machine contemplated by my invention may be in the form of a housing or cabinet, capable of being readily moved from one position to another or where the machine is installed in retail markets, a number of the machines may be built into the walls or partitions of the market building.

The front of the housing or cabinet is closed by a readily removable glazed panel 15 which should be equipped with suitable means to enable it to be locked to the housing and the lower end of the panel 15 is spaced a short distance above a horizontally disposed partition 16 that is located in the lower portion of the cabinet a short distance above the bottom 12.

Such construction provides below the glazed panel 15 an opening 17 through which the vended goods may be readily removed by the purchaser and the space below the partition 16 provides a storage chamber 18 for the vended article supporting rods after the same are released from their positions beneath the supported articles.

Formed in the partition 16 is a series of transversely disposed slots 19 which permits the supporting rods to drop through the partition into the storage chamber 18. A drawer (not shown) for the reception of the rods may be removably positioned in said chamber or a door or removable panel, such as 20, may be arranged to normally close an opening in the rear wall of the cabinet below the partition 16.

Spacing blocks 21 are secured on the inner faces of the side walls 10 of the cabinet just below the top 11 and above the partition 16, said blocks being disposed in horizontal rows and secured to said blocks are the ends of vertically disposed straps 22, preferably of thin wood or metal, and the members of each set of these straps are spaced apart throughout their lengths to form vertically disposed slots 23 for the reception of the ends of the rods that support the articles to be vended and which slots are open at both ends.

Where rods are utilized for supporting the vended articles, said rods which are designated by the numeral 24 are formed of heavy wire and integrally secured to the ends thereof are substantially cylindrical heads 25.

Arranged for longitudinal sliding movement, preferably between the right hand one of the walls 11 and the straps 22 supported thereby, is a horizontally disposed actuator rod 26 with the forward portion of which is associated an expansive coil spring 27 that yieldingly resists the outward movement of said rod and that portion of the rod that projects from the front of the cabinet passes through the lower portion of a housing 28 that contains conventional coin actuated mechanism that normally locks the rod against movement in both directions. The forward end of the rod in front of housing 28 carries a small handle 29. Under normal conditions the rod 26 is held at its rearward limit of movement by spring 27 and upon the insertion of a coin of proper value into the housing 28, the rod locking means is released so that said rod may be pulled forwardly a sufficient distance to effect release of the lowermost set of article supporting rods 24.

The rear end of the rod 26 is pivotally connected to one end of a horizontally disposed lever 30 that is fulcrumed at its center to a bracket 31 that is secured to the rear wall 13 of the cabinet.

Pivottally connected to the end portions of lever

30 are the rear ends of horizontally disposed rails designated generally by the numeral 32 and which are mounted for longitudinal sliding movement upon suitable ledges that are secured to the inner faces of the side walls 10. These rails provide supports for the ends of the lowermost set of article supporting rods 24 and said rails being constructed so as to release said lowermost set of article supporting rods, when the actuator rod 26 is pulled forwardly.

Inasmuch as the rails 32 are connected to lever 30 so that when the latter is swung upon its axis, said rails move in opposite directions, these rails must be made in rights and lefts in order to function properly and permit the release of the lowermost set of article supporting rods.

Each rail 32 comprises a horizontally disposed intermediate portion 33, from the outer edge of which depends a vertically disposed flange 34 and projecting upwardly from the inner edge of the intermediate portion 33 is an upstanding longitudinally disposed flange 35.

Formed in the vertical flange 35 and spaced apart longitudinally thereof are openings 36, there being the same number of these openings as there are slots 23 between the straps 22.

The metal in flange 35 above the rear portions of the openings 36 on the right hand one of the rails 32 and the metal above the forward portions of the openings 36 on the left hand one of the rails 32 are cut away to form short slots or openings 37 and those portions of the metal in flange 35 above the openings 36 in front of the slots 37 in the right hand rail 32 and to the rear of the slots in the left hand one of the rails, provide horizontally disposed fingers 38 upon which the end portions of the merchandise supporting rods 24 normally rest.

Formed in the horizontal portion 33 of each rail 32 and extending laterally from the end of opening 36 beneath the finger 38 is a transversely disposed slot 39 that communicates with an opening 40 that is formed in member 33. The width of slots 39 is slightly greater than the diameter of the rods 24 and the openings 40 are of sufficient size to permit the downward passage therethrough of the heads 25 that are carried on the ends of the merchandise supporting rods.

In Figs. 4a and 5 I have illustrated portions 50 of the rod supporting rails that are positioned on the right hand one of the walls of the cabinet and Figs. 6 and 7 illustrate portions of the rails that are located on the left hand side wall of the cabinet.

Under normal conditions or with the machine serviced and ready for operation, the spring 27 associated with pull rod 26 maintains the rod supporting rails 32 in position so that the end portions of said rods rest on the fingers 38 and said fingers 38 and the slots 39 and openings 40 being disposed in transverse alignment with the slots 23 between the straps 22.

To service the machine, a plurality of rods are dropped downwardly through the slots 23 with the heads on the ends of said rods disposed behind the straps 22 and these rods come to rest with their end portions resting on the fingers 38 of the rails 32. A package of merchandise is now placed on the lowermost set of rods as illustrated in Figs. 2 and 3 and a second set of rods is now introduced and permitted to move downwardly through the slots 23 until said rods rest on top of the article of merchandise resting on the first set of rods. A second article of merchandise is now placed on top of the second set of rods and

this packing arrangement is continued until the last article of merchandise introduced occupies a position in the top of the chamber within the cabinet.

A purchaser to obtain one of the packages or articles of merchandise in the cabinet, inserts a coin of proper value in the housing 28, thereby releasing the coin actuated mechanism that normally holds pull rod 26 against movement and after the coin has been inserted, the handle 29 is engaged and rod 26 pulled forward to its limit of movement, thereby compressing and storing power in spring 27.

This forward movement of rod 26 moves the adjacent right hand one of the rails 32 forwardly and lever 30 swinging on its fulcrum 31 moves the left hand one of the rails 32 rearwardly.

As this simultaneous movement of the rod supporting rails takes place, the fingers 38 supporting the lowermost set of merchandise carrying rods will be withdrawn from their positions beneath said rods and when the openings 37 reach positions beneath said rods, the latter will drop through said openings into the openings 36 with the heads 25 on the ends of said rods resting on the intermediate portions 33 of the rails.

After the pull rod 26 has been drawn forwardly to its limit of movement, the pull upon said rod is released and the power stored in spring 27 will move said rod rearwardly into the machine and thus, the right hand one of rails 32 will be likewise moved rearwardly and the left hand one of said rails will move forwardly.

These movements bring the openings 39 and 40 into a position where the ends of the rods will drop through said openings and said rods after passing downward through the lower portions of the slots 23 will drop through the slots 19 in partition 16 and will thus be delivered to the storage chamber 18. Thus as the supports for the lowermost article of merchandise drop away from the supported article, the latter will drop onto the partition 16 from whence it may be removed through opening 17 below glazed panel 15.

As the lowermost article of merchandise is vended as just described, the entire series of rods carrying the article of merchandise will drop a distance equal to the height of one article and thus, the rods that support the lowermost article will come to rest upon the fingers 38 on the rails 32 which were returned to their normal positions through the action of spring 27.

In the modified construction of the vending machine illustrated in Figs. 9 to 14 inclusive, the vended article support instead of comprising a plurality of rods takes the form of a skeleton rack 41, preferably composed of wire and including a rod 42 provided on its ends with heads 43 and which is practically the same as the rod 24. Extending from the rod 42 in the same direction are a plurality of arms 44 on the forward ends of which are located short tubes 45 that perform the functions of rollers. Obviously, this rack may be formed from pressed sheet metal.

When such rack is used for supporting articles or packages to be vended, it is desirable that said racks successively assume an inclined position just above the slotted partition within the bottom of the cabinet in order that the articles may readily discharge from the racks when the lowermost one has been released as a result of manipulation of the rod 26.

The racks 41 are introduced into the cabinet between the slats 22, each rack bearing a package of merchandise and the ends of the rod 42

projecting into the rear pair of slots 23. Prior to the placing of the first one of the racks into the cabinet and which rack becomes the lowermost one of the series of racks that supports the articles within the cabinet, two of the rods 24 provided on their ends with heads 25 are positioned, one in the slots 23 beneath the rod 42 that forms a part of the lowermost rack and the other rod is positioned beneath the front portions of the parallel arms 44, with the ends of said rod projecting through a pair of the slots 23. Thus, the heads 43 on rod 42 normally rest on the heads 25 of the rear one of the inserted rods 24.

When the vending machine is operated by pulling rod 26 forwardly, the rod 24 that is positioned beneath the rod 42 on the lower one of the racks and which rod 24 rests on a pair of the fingers 38 of the rails 32 will, as said rails 32 are actuated, drop through the slots 37 into the openings 36 and the heads 25 on the ends of said rod will rest on the horizontally disposed portions 33 of the rails 32 simultaneously with the foregoing action, the inserted rod 24 that provides a support for the front portion of rack 41 will drop through the corresponding slots 36 and openings 37 so that the heads on the ends of said rod rest on intermediate members 33 of the rails 32.

When the pull on rod 26 is released, the rails 32 will move longitudinally in opposite directions as heretofore described and the ends of the inserted rod 24 and the heads 25 thereon will drop through the openings 39 and 40 and said rods will pass downward through the corresponding slot in the partition 16 and from thence into the chamber 18 beneath said partition.

As the rails 32 return to their normal positions under the influence of the spring 27, the fingers 38 upon which the ends of the rear one of the rods 24 have just been positioned will move beneath the ends of rod 42 forming a part of the rack 41 so as to provide a support for said rod.

As the action just described takes place, the front one of the inserted rods 24 dropping downwardly from the front of the rack 41 will permit the latter and the article supported thereby to swing downward into an inclined position as illustrated in Fig. 9, thus enabling the supported article to be readily removed through the opening in the front wall of the cabinet beneath glazed panel 15.

As the rack 41 swings downward into an inclined position as just described and illustrated in Fig. 9, the end portions of the rod 42 resting upon a pair of the fingers 38 provides an axis for said rack and on the subsequent actuation of the vending machine, the rod 42 on the rear end of the lowermost rack performs the functions of the inserted rod 25 that was used in connection with the lowermost one of the racks in the previous actuation of the machine and as the rails 32 are moved lengthwise on the succeeding operation, the rod 42 at the rear end of the inclined rack will ride off the fingers 38 on which it is supported and on the succeeding longitudinal movement of the rails 32, the ends of said rod and the heads 43 thereon will drop through the openings 39 and 40.

As the lowermost one of the racks is thus released, it will by gravity move downward onto the top of the slotted partition 16 and will pass through the slots therein into chamber 18 and to enable this operation to take place, the parti-

tion 16 must be provided with crossed slots for the accommodation of the arms 44, rod 42 and the rollers 45 (see Fig. 10).

As the lowermost rack 41 moves downward from an inclined to a horizontal position on the perforated partition, the rollers 45 will roll a short distance forwardly on said partition, thus eliminating any friction that otherwise might occur between the front portions of the arms 44 and the slotted partition.

In Fig. 16 I have shown a modified construction for spacing the inserted rods 24 a predetermined distance apart and which arrangement may be used with certain forms or packages of merchandise that are vended in the machine.

In this construction, channel-shaped members 46 are pivoted at 47 to a rod 24 near its ends and associated with the pivots of said members are springs 48 that normally tend to swing the members 46 downwardly against the rod. When the members are swung upwardly into vertical positions as illustrated in Fig. 16, they serve to support a merchandise carrying rod 24 a substantial distance above the rod to which said members 46 are pivoted and said pivoted members are retained in their vertical positions by the weight of the supported rod and the merchandise positioned thereupon.

When the rod 24 to which the members 46 are pivoted is released to drop downward through the perforated partition, the members 46 will swing downward under the influence of the springs 48 so as to lie directly on top of the end portions of the rod to which they are pivoted and thus pass with said rod through the slots in partition 16 into the compartment 18.

In the modified construction illustrated in Fig. 18, I have shown a merchandise supporting rod 49 provided on one end with a head 50 that is adapted to engage on the upper edge of a sliding rail 51, similar in construction and function to rail 32, and the opposite end of said rod carries a spherical head 52 that is supported by a fixed rail 53.

In this construction, the end of the rod 49 provided with the head 50 is released as the sliding rail 51 moves forward and then backward, as hereinbefore described, and when the end of the rod drops through the openings in the sliding rail 51, the rod will swing downward into a substantially vertical position with the head 52 functioning as a pivot and at the end of such swinging movement, the rod will drop while in a vertical position through an opening in the slotted partition that is arranged in the lower portion of the cabinet.

In Fig. 19 I have illustrated a modified construction wherein the slotted partition that is arranged in the lower portion of the cabinet above the chamber 18 into which the rods and racks drop, is inclined with its lowermost front portion projecting through the opening 17 beneath the glazed panel 15 and which arrangement facilitates the discharge and removal of the vended merchandise from the cabinet.

Thus it will be seen that I have provided a

vending machine that is relatively simple in construction, inexpensive of manufacture and very effective in performing the functions for which it is intended.

It will be understood that minor changes in the size, form and construction of the various parts of my improved vending machine, may be made and substituted for those herein shown and described, without departing from the spirit of my invention, the scope of which is set forth in the appended claims.

I claim as my invention:

1. In a vending machine, a housing including side walls, a plurality of vertically disposed spaced guide ways on said side walls, a plurality of independently operating merchandise supporting means, heads on said supporting means, which heads are arranged for sliding movement in said guide ways and releasable means for supporting the lowermost merchandise supporting means, said releasable means including horizontally disposed sliding rails provided with openings and slots for the reception and passage of the heads on said merchandise supporting means.

2. A vending machine as set forth in claim 1 and manually operable means for effecting the release of said releasable means.

3. A vending machine as set forth in claim 1 and with a compartment in the lower portion of said housing for the reception of the supporting means after the supported merchandise is discharged therefrom.

4. In a vending machine, a housing having side walls in one of which is formed a dispensing opening, a plurality of vertically disposed spaced guide ways on said side walls, a plurality of independently operating merchandise supporting means having ends arranged for sliding movement in said guide ways, rails arranged for sliding movement in said cabinet and extending across the lower portions of said guide ways for supporting the lowermost one of said merchandise supporting means and said sliding rails being provided with openings which permit the ends of said supporting means to drop from said rails.

5. A vending machine as set forth in claim 4, with a compartment in the lower portion of said cabinet and a partition above said compartment, which partition is provided with slots to permit the downward passage of the merchandise supporting means through said partition.

6. In a vending machine, a housing including side walls, a plurality of vertically disposed spaced guide ways on said side walls, a plurality of independently operating merchandise supporting means having parts that are arranged for sliding movement in said guide ways, releasable means for supporting the lowermost merchandise supporting means, there being a merchandise discharge opening formed in the front wall of the cabinet and a slotted partition located in the lower portion of the cabinet, with its front end disposed in the lower portion of the merchandise discharge opening.

ROY E. ELVERS.
